DESIGN FOR A DRESS

Pauline Fracchia, New York, N. Y.

Application May 3, 1939, Serial No. 84,739

Term of patent 3½ years

To all whom it may concern:

Be it known that I, Pauline Fracchia, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The characteristic feature of my design resides in the combination on the specific princess dress disclosed of the specific button trim around the neck line and down the front and on the pockets and sleeves as shown.

I claim:

The ornamental design for a dress, substantially as shown and described.

PAULINE FRACCHIA.
